UNITED STATES PATENT OFFICE

100,097

DESIGN FOR AN AUTOMOBILE SERVICE STATION ISLAND GROUP BASE UNIT

Alexander P. Fox, University City, Mo., assignor
to Lincoln Engineering Company, St. Louis,
Mo., a corporation of Missouri

Application April 1, 1936, Serial No. 61,891

Term of patent 14 years

To all whom it may concern:

Be it known that I, Alexander P. Fox, a citizen
of the United States and a resident of University
City, St. Louis County, Missouri, have invented a
new, original, and ornamental Design for An
Automobile Service Station Island Group Base
Unit, of which the following is a specification,
reference being had to the accompanying drawing,
forming part thereof, in which the single
figure is a perspective view of the automobile

service station island group base unit embodying
my new design.

I claim:

The ornamental design for an automobile serv-
ice station island group base unit, substantially
as shown.

In testimony whereof, I have signed my name
to this specification this 28th day of March, 1936.

ALEXANDER P. FOX.
